PHONOGRAPH RECORD RACK

Oliver Sabin, New York, N. Y., assignor to Paul Puner, I. R. Gwirtz, and Oliver Sabin, co-partners, doing business as Century Distributors, New York, N. Y.

Application March 8, 1943, Serial No. 478,364

3 Claims. (Cl. 211—40)

My invention relates to a rack for phonograph records or for objects of similar shape, and more particularly, to a rack adapted to keep a large number of disk-shaped bodies in a position where said bodies are vertically inserted in the rack.

An object of my invention is to provide a rack of this kind which can easily be transformed from a flat or not bulky condition adapted for shipment or storage into the condition of use, and vice versa.

Other objects are to provide a structure of such a rack which can be easily, inexpensively and quickly manufactured, assembled and dismounted, which can be made from non-metallic material, which has a low weight and which can be shipped inexpensively.

Further objects are to provide a rack which receives a large number of records or disks, which holds the same safely in vertical positions separate from each other, which supports the same at a height where they do not touch the table or bases on which the rack rests, and which has a good stability.

One of the main features of my invention is the use of a resilient plate or sheet having a wide area and a relatively small thickness and containing slots for the insertion of the records or disks. Still further objects are to provide such a plate which can be repeatedly bent from a flat condition into a bent condition and vice versa which can be bent and used bent in opposite directions, which acts resiliently or spring-like in either bent condition, and which retains this quality after repeated bending operations.

Still other objects are to provide simple and reliable means to hold said plate in bent condition and to support the same in a position adapted to receive the records or disks. Further objects and advantages will appear from the following description of an exemplifying embodiment of the invention, from the appended claims and from the drawing in which:

Figure 1 shows a view of an embodiment of the invention in a condition adapted for shipment.

Figure 2 shows a view of the same embodiment seen from the right side in Figure 1.

Figure 3 shows a side view of the same embodiment in the condition of use with two inserted records.

Figure 4 shows a front view of the embodiment shown in Figure 3.

Figure 5 shows a view of the embodiment

shown in Figures 3 and 4, seen from the upper side.

Referring to the drawing, numeral 1 indicates a thin plate or sheet made from resilient material, preferably from fibre, veneer, pasteboard or any other suitable non-metallic material. A large number of parallel slots 2 are cut through the plate 1. The slots 2 end at some distances from two opposite edges of the plate 1 whereby two coherent margins are left at said edges of the plate. In the shown embodiment, the plate 1 has a rectangular area which is sufficiently broad for slots 2 of suitable length and for marginal parts of suitable width and which is sufficiently long for the arrangement of a large number of slots 2 with separating distances. These slots may run in an oblique direction, but preferably they are cut in a direction perpendicular to two opposite edges of the plate 1. The number of the slots may be larger than shown in the drawing, their width being shown relatively exaggerated for the sake of clearer representation.

The said marginal parts of the plate 1 are stiffer than the slotted part of 1 and may be made still stiffer by affixing a reinforcing or holding ledge or ridge 3 to each of said marginal parts. Preferably, said ledge is made from wood and has a longitudinal slot 4 at one of its smaller sides for the insertion of the marginal part of 1. The part of the plate 1 which is inserted in said slot 4 of the ledge 3 may be glued to the ledge or held by pressure or affixed by any other suitable means. In the shown embodiment, the ledge 3 covers the edge of the plate 1 and a portion of the width of the marginal part thereof. If the ledge covers the entire width of the marginal part, the ledge forms the end of the slots 2. In the latter case, the slots may originally extend throughout the plate which, in this case, is divided into a number of strips held together by the ledges which determine the length of the slots 2 and the width of the marginal parts.

In the condition of use, the plate 1 is so bent that that part thereof which lies in the middle between said two marginal parts forms a curved top, and that the marginal parts or the ledges form lower ends inserted into slots 6 of bars or crossing ledges 5, preferably made from wood. Each bar 5 extends from one ledge 3 to the other and has two slots 6, one for each ledge 3. The distance between the two slots 6 of one bar 5 is smaller than the width of the plate 1 or the distance between the ledges 3 whereby

the plate can be inserted only in bent position into the slots 6, and the bar holds the inserted plate in the bent position.

The slots 6 open to the upper sides of the bars 5. The distance between the openings of two slots of one bar may be smaller than the distance between the bottoms of said two slots, that is to say, the slots are cut in directions obliquely spreading to the lower side whereby the marginal parts of the plate 1 are held in oblique directions determining tangents of the curvature of the plate 1.

Preferably, the bars 5 are positioned parallel to each other, their lower sides forming the bases of the rack and resting on a table or on any other surface supporting the rack. Two bars 5 positioned at the ends of the ledges 3 are used in the shown embodiment.

The length of the slots 2 is determined by the diameter of the disks to be inserted, the ends of said slots, in the bent position of the plate 1, having a distance smaller than the diameter of the disks whereby disks are prevented from falling through the slots. The marginal parts and the bars 5 are so measured that the inserted disks do not reach downward as far as the bases of the bars or do not touch the table on which the rack rests. Preferably, the top curvature of the plate 1 reaches higher than the center of the disks whereby the disks are well secured against tilting. Two records 7 are shown inserted in Figures 3, 4 and 5, the remaining slots 2 being ready for the reception of further records.

The original condition of the plate 1 is flat or even. When the plate 1 is inserted in the bars 5 as described, the resiliency of the plate tends to spread the marginal parts whereby the ledges 3 are pressed against the outer walls of the slots 6 and a firm grip results, even if the slots 6 are broader than the ledges 3. Repeated bending of the plate 1 in the same direction or continual use of the plate bent in the same direction may lead to weakening of this spring-like quality, and the plate may not return readily into the flat condition. This drawback is easily avoided by using the plate bent alternately in the one or in the opposite direction.

The bars and the plate can be easily separated and packed or stored without requiring much space, for example, in the position shown in Figures 1 and 2. If a number of racks is to be packed, the bars of all racks may be arranged in one flat row, and the plates may be put one over the other in flat positions whereby storage and the shipment is facilitated.

I desire it understood that my invention is not

confined to the particular forms and uses shown and described, the same being merely illustrative, and that the invention may be carried out in other ways without departing from the spirit of my invention as it is obvious that the embodiments shown and described are only a few of the many that can be employed to attain the objects of my invention.

It should be understood that although I have described the slotted plate 1 as being made of non-metallic material, it may nevertheless, in some instances, be made of metal or other material having the desired resiliency.

Having described the nature of my invention, what I claim and desire to secure by Letters Patent is:

1. A rack for phonograph records or the like, comprising a plate or sheet made of resilient material and having two marginal parts at opposite edges and a plurality of slots cutting said plate and extending from one of said marginal parts to the other, two ledges each of which is affixed to one of said marginal parts, and at least one bar having two slots cut into one of its sides, each of said latter slots having a width large enough to grip one of said ledges, the distance between said latter slots being smaller than the distance between said ledges whereby said bar is adapted to hold said plate in a resiliently bent position.

2. A rack for phonograph records or the like, comprising a plate or sheet made of resilient material and having a plurality of substantially parallel slots cutting said plate in a direction from one of its edges to the opposite edge, two ledges each of which is affixed to one of said opposite edges, and at least one bar having two slots cut into one of its sides, each of said latter slots having a width large enough to grip one of said ledges, the distance between said latter slots being smaller than the distance between said ledges whereby said bar is adapted to hold said plate in a resilient bent position.

3. A phonograph record rack comprising a resilient normally flat plate having oppositely disposed marginal ends and a series of slots for the reception of phonograph records, and supporting bars provided with an angular slot at each end, adapted to removably engage the marginal ends of the resilient plate when in flexed position, the distance between the marginal ends of the plate being greater than the distance between the angular slots in each supporting bar, whereby the plate can be held in the flexed condition by the bar.

OLIVER SABIN.
